ABSTRACT: An electrical contact for use in a card-edge connector has a nose portion with a bifurcated section comprising a pair of legs separated by a bifurcating slot. At least one chamfered surface is coined into the contact below the bifurcating slot, and a bus strip is provided with a similar chamfered surface for mating with the chamfered surface on the contact when the bus strip is inserted into the bifurcating slot. In an alternative embodiment of the invention, a slit, defined in part by four chamfered surfaces, is provided in the tail portion of the contact, and the bus strip is inserted into the slit so that the chamfered surfaces of the bus strip mate with the chamfered surfaces on the tail portion of the contact. A further embodiment of this invention comprises a card-edge contact which has flat, parallel, uncoined surfaces below the bifurcating slot, and a bus strip which has a contact-receiving slot defined, in part, by inwardly facing projections having contact-engaging surfaces thereon. The bus strip is inserted into the bifurcating slot of the contact with the flat, parallel, uncoined surfaces of the contact positioned within the contact-receiving slot of the bus strip.

BUS STRIPS AND CONTACTS

This application is a continuation-in-part of my application filed Sept. 12, 1968, now U.S. Pat. No. 3,562,805, granted Feb. 9, 1971. This invention relates to the mechanical and electrical interconnection of contacts with bus strips.

In electronic equipment groups of printed circuit boards carrying various circuit components are frequently interconnected to provide electrical circuit systems. In one interconnection system, each printed circuit board is plugged into an electrical connector which is mounted on the front face of a metal plate. The metal plate provides a ground plane for the electrical circuits on the printed circuit boards as well as a mechanical support for the assembled printed circuit boards and connectors.

Each connector is comprised of a casing of insulating material in which are mounted a plurality of contacts. Each contact has a tail section that passes through and extends beyond the rear face of the metal plate upon which the connector is mounted. The tail sections of the contacts are usually square or rectangular in cross section for permitting conventional automatic back panel wiring techniques, such as solderless wrapping or the like, to be used to establish the required electrical interconnections and to permit power and signal inputs to be applied to the network and to permit signal outputs to be taken therefrom.

In apparatus of the type described, each printed circuit board generally requires one or more power inputs, and for this purpose a voltage bus assembly is provided. A voltage bus assembly is comprised of a plurality of electrically interconnected contacts which mate with those conductive pads on the printed circuit boards, which require power at the same voltage level.

One type of voltage bus assembly is disclosed in the U.S. Pat. of Ruehleman/Slobodzian, No. 3,559,604, issued 2/2/71, and assigned to the present assignee. This voltage bus assembly is manufactured as a unitary structure by passing a continuous strip through a progressive die in the direction of the longitudinal axis of the strip. The nose portions of the various contacts are stamped from a portion of the strip on one side of the longitudinal axis, and the tail portions are stamped from a portion of the strip on the other side of the longitudinal axis. The center section of the strip provided the electrical and mechanical interconnection between the various nose and tail portions. Tolerance variations in the manufacture of the bus assembly, and the insulating casings adapted to receive the bus assembly present alignment problems in the assembling operation. The unitary construction of the bus assembly permits only limited pivotal movement between the nose and tail portions of such assembly on the one hand, and the bus strip of the assembly on the other hand. This limited movement, accompanied by the fact that automatic assembly equipment presently is not available, makes the alignment and assembly of the bus assembly with the insulating casing a difficult, time-consuming operation.

Another disadvantage of the bus assembly shown in said Ruehleman et al. applications is its lack of versatility. Because of the unitary construction of the bus assembly, any defect or operational failure of a single nose portion or tail portion necessitates replacement of the complete unitary structure. The complete replacement of the bus assembly involves a waste of material, and is difficult to effect because of the large number of nose and tail portions which must be removed from and reassembled with the insulating casing.

A bus assembly comprised of individual contacts and a separate bus strip is known. This assembly is comprised of a card-edge contact having a nose portion comprised of a pair of legs separated by a bifurcating slot. Immediately below and adjacent to the termination of the slot, a laterally extending clip is provided with a pair of opposed clamping fingers which will electrically and mechanically engage a flat, electrically conductive strip inserted into the bifurcating slot of the contact. These clip extensions on the contacts limit the minimum spacing between adjacent contacts. In fact, such contacts were designed for use in a bus assemblies wherein adjacent contacts

are spaced on 250- inch centers or greater. This spacing positioned in separate, adjacent, single readout connectors; however, in dual readout connectors wherein adjacent contacts are spaced as close as 0.100 inch, contacts with clip extensions

5 are not acceptable. For purposes of definition in this application, a "single readout connector" is defined as one having contacts positioned on only one side of a circuit board receiving slot for electrically engaging conductive tracks on only one side of a circuit board, and a "dual readout connector" is defined as one having contacts on both sides of a circuit board receiving slot for electrically engaging conductive tracks on both sides of a circuit board.

To accommodate the clip extensions, the contacts are stamped from strip material on approximately 0.5-inch centers, whereas contacts without clip extensions are stamped on less than 0.25-inch centers. Thus, more waste is encountered in manufacturing contacts with clip extensions than is the case in manufacturing contacts without such extensions.

15 The bus assemblies of the present invention also comprise separate contacts and bus strips, thus eliminating the main assembly difficulties encountered in utilizing the unitary bus assembly disclosed in said Ruehleman et al. application. Moreover the contacts of this invention do not have clip extensions and therefore the assembly of the present invention can be utilized in dual readout connectors wherein contact spacings as small as 0.100 inch may be required. Also, the problem of excessive waste of material is alleviated through the elimination of the clip extensions.

20 30 One bus assembly of the invention of the parent case hereof utilizes contacts which have a nose portion and a tail portion interconnected by a body portion. The body portion is utilized to firmly retain the electrical connector. The nose portion is defined by a bifurcating section comprises a pair of legs separated by a bifurcating slot. Each leg has a front surface with a curved portion thereof adapted to engage to a conductive track of a circuit board when the circuit board is positioned within a circuit board receiving slot in the insulating casing of an electrical connector.

35 40 The bifurcating slot extends downwardly from an upper surface of the nose section of the contact and terminates short of the body portion of said contact. An elongated slit is in alignment with the axis of the slot and is positioned in a section of the contact which is disposed between the body portion of the contact and the termination of the slot. Chamfered surfaces are provided on the contact adjacent the slit. An elongated bus strip is provided with contact-receiving slots extending through the lower surface thereof in a perpendicular direction to the direction of elongation of the strip, and chamfered surfaces are provided on the bus strip adjacent the contact-receiving slots for engaging the chamfered surfaces on the contacts when the bus strip is inserted into the bifurcating slots of such contacts. The mating chamfered surfaces provide excellent electrical and mechanical interconnections between the contacts and bus strip.

45 55 In a second embodiment of the invention of the parent case thereof contacts are utilized which have the same general configuration as the contacts utilized in the first embodiment with the exception that the slit and chamfered surfaces are omitted. The region of the contact between the body portion and the termination of the bifurcating slot is comprised of a pair of flat, substantially parallel, uncoined surfaces. An elongated bus strip is provided with contact-receiving slots extending through the lower surface thereof in a perpendicular direction to the direction of elongation of said strip. The inner surfaces defining each slot are comprised of contact-engaging surfaces which define a gap therebetween. The contact engaging surfaces on the bus strip engage the flat surfaces in the contacts when the bus strip is inserted into the bifurcating slots of such contacts.

60 70 75 The more important features of this invention have thus been outlined rather broadly in order that the detailed description thereof which follows may be better understood, and in order that the contribution to the art may be better ap-

preciated. There are, of course, additional features of the invention that will be described hereinafter and which will also form the subject of the claims appended hereto. Those skilled in the art will appreciate that the conception upon which this disclosure is based may readily be utilized as a basis for designing other structures for carrying out the several purposes of this invention. It is important, therefore, that the claims to be granted herein shall be interpreted with sufficient breadth to prevent the appropriation of this invention by those skilled in the art.

DRAWINGS

FIG. 1 is a perspective view of a novel contact;

FIG. 2 is a front view of one embodiment of the bus strip of this invention;

FIG. 3 is an assembly view of the contacts in an insulating casing; such contacts being interconnected by the bus strip of this invention, and a section of one of the contacts being removed to show details of construction;

FIG. 4 is a sectional view taken through line 4—4 of FIG. 3;

FIG. 5 is an assembly view, similar to FIG. 3, of a second embodiment;

FIG. 6 is a sectional view taken through line 6—6 of FIG. 1;

FIG. 7 is a perspective view of a contact utilized in the embodiment of this invention;

FIG. 8 is a sectional view taken through line 8—8 of FIG. 7;

FIG. 9 is a view of the retaining member as viewed from the right of FIG. 10; and

FIG. 10 is an assembly view, similar to FIG. 3, of the embodiment of this invention.

Referring now to the drawings, FIG. 1 shows a perspective view of a contact comprising a nose portion 12 and a tail portion 16 interconnected by a body portion 14. The nose portion 12 has a bifurcated section comprising a pair of legs 18 (front leg partially cut away) separated by a bifurcating slot 19. The bifurcating slot 19 terminates at 23, and a slit 21 extends downwardly therefrom in alignment with the axis of slot 19. The slit 21 terminates in a bridging portion 28 which is adjacent body portion 14 of the contact. Each leg 18 is provided with a rear surface 22, an inner surface 24, and a front surface 20. The front surface 20 has a curved circuit board-engaging portion 32 for engaging the conductive track of a printed circuit board. Regions of the

contact adjacent slit 21 are coined to form four chamfered surfaces 26 (FIGS. 1, 4, and 6). The bridging portion 28 at the end of slit 21 is comprised of comprised of chamfered surfaces 30 (FIGS. 1 and 2). The slit 21 need not be a through slit but can be as a blind slit.

The body portion 14 of the contact is utilized to retain the contact 10 within insulating housing 72 of an electrical connector 70 (FIG. 3). The tail portion 16 of the contact is comprised of a straight post portion which is suitable for automatic wire wrapping or other solderless-type connections. It is understood that other suitable terminations can be provided on the contact of this invention.

Referring now in detail to FIGS. 2, 3, and 4, a bus strip 40 is disclosed which will mate with contact 10. The bus strip 40 is comprised of elongated, substantially parallel, side surfaces 54 which are interconnected by an upper surface 42 and a lower surface 44. A plurality of contact-receiving slots 46 extend through the side surfaces 54 of the strip 40 from the lower surface 44 toward the upper surface 42 in a perpendicular direction to the direction of elongation of said side surfaces 54.

The contact-receiving slots 46 are defined, in part, by inner surfaces 52 which face each other and are disposed in planes that are substantially perpendicular to the planes of the side surfaces 54. The inner surfaces 52 and side surfaces 54 are interconnected by chamfered surfaces 48 which are adapted to mate with the chamfered surfaces 26 of contact 10. The inner surfaces 52 and chamfered surfaces 48 terminate short of lower surface 44 of the bus strip 40, and inclined surfaces 50

interconnect said chamfered surfaces and inner surfaces with lower surface 44.

A relief slot 56 is interposed between each pair of contact-receiving slots 46. These relief slots extend through the side surfaces 54 of the bus strip 40 and are parallel to contact-receiving slots 46. Each relief slot 56 and its adjacent contact-receiving slot 46 defines a leg 58 therebetween which is resiliently deflectable in the plane of the bus strip 40 to provide a resilient interconnection between contact 10 and bus strip 40. Relief openings 62 are provided at the end of relief slots 56 remote from lower surface 44 to further contribute to the resiliency of legs 58. Since legs 58 are resiliently deflectable, the bus strip can be assembled easily with contacts which are mounted within insulating casings despite some slight misalignment of parts due to tolerance variations.

FIG. 4 shows the manner in which the chamfered surfaces 48 of the bus strip 40 mate with chamfered surfaces 26 of the contact 10. The bus strip 40 is inserted into the bifurcating slot 19 of the contacts 10 with each contact-receiving slot 46 aligned with a respective slot 21 in each of the contacts. The bus strip 40 is then pressed downwardly to cause chamfered surfaces 48 on the bus strip to frictionally engage with, and slide against chamfered surfaces 26 of the contact. The sliding, frictional engagement between the four chamfered surfaces on each contact 10 and the corresponding surfaces on the bus strip 40 will remove any oxide built up between such surfaces to insure that electrical continuity will exist.

In the undeflected condition of legs 58, the distance between facing inner surfaces 52 defining each contact-receiving slot 46 is smaller than the transverse dimension of the contact in the region of the slit 21 and chamfered surfaces 26. This arrangement causes adjacent legs 58 to be resiliently urged apart upon assembly of the bus strip 40 with contact 10 to insure that excellent mechanical and electrical continuity is maintained.

In assembled condition, clearance is provided between inclined surfaces 50 on bus strip 40, and the chamfered surfaces 30 on each contact 10 to prevent adjacent legs 58 from being forced apart due to the sliding interaction between said surfaces, which would thereby destroy the electrical and mechanical continuity between the chamfered surfaces of bus strip 48 and contact 10.

FIG. 3 shows an electrical connector 70 which has a pair of contacts 10 therein which has a pair of contacts 10 therein which are interconnected by bus strip 40. The electrical connector 70 is comprised of insulating housing 72 and a plurality of pairs of contacts 10 (only one pair being shown in FIG. 3); the insulating housing being mounted to a metal plate 80 through any suitable connection means such as hubs on said insulating casing. Slots are provided through sidewalls 73 of the insulator to receive the bus strip therein. The circuit board may have circuitry on opposite sides thereof. Electrical terminations to both sides of the circuit board are effected by each pair of contacts 10 in insulating housing 72. The bus strip for electrically interconnecting the pair of contacts 10 shown in FIG. 3 is provided with contact-receiving slots 46 which are spaced the same distance across the strip as the spacing between such contacts 10. The contact spacing between each pair of contacts 10 in a dual readout connector is usually between 0.100 inch and 0.002 inch.

It is understood that usually a plurality of electrical connectors are mounted side by side on metal plate 80 with sidewalls 73 adjacent to one another, and the slots in said sidewalls being aligned to receive the bus strip 40 in a plane which is substantially perpendicular to the circuit board receiving slots 76 to thereby electrically interconnect contacts within each electrical connector which require power at the same voltage level.

Referring now to FIG. 5, a contact 10A has a nose portion comprised of a pair of legs separated by a bifurcating slot as described with respect to the contact disclosed in FIG. 1. The region of the nose portion of contact 10A which is between the body portion of said contact and the termination of the

bifurcating slot is comprised of a pair of flat, substantially parallel, surfaces 94 which are neither slit nor coined.

The bus strip 40A which is utilized to interconnect contacts 10A is comprised of elongated, substantially parallel, side surfaces 54A which are interconnected by a lower surface 44A. A plurality of contact-receiving slots 46A are spaced along the bus strip in the direction of elongation of said bus strip on the same spacing as the spacing between the contacts to be interconnected. Each contact-receiving slot 46A extends through the said surfaces 54A in a perpendicular direction to the direction of elongation of said bus strip. Each slot is defined, in part, by inner flat surfaces 88, which face each other, and which terminate short of the lower surface 44A. Inwardly facing projections 90 on strip 40A have contact-engaging surfaces 48A thereon defining a gap therebetween; the distance between the contact-engaging surfaces 48A being less than the transverse dimension between the flat, parallel surfaces 94 of contact 10A. A pair of relief slots 56A are positioned between each pair of contact-receiving slots 46A; one of said relief slots 56A forming a leg 58A with its adjacent contact-receiving slot 46A, and the other relief slot 56A forming a leg 58A with its adjacent contact-receiving slot 46. The arrangement of relief slots as shown in bus strip 40A can also be utilized with the bus strip 40, and the arrangement of relief slots 56 shown in bus strip 40 can also be utilized in the bus strip 40A. The bus strips have the versatility of being utilizable with either dual readout connectors, single readout connectors, or a combination of both types of connectors, single readout connectors, or a combination of both types of connectors.

The bus strip 40A is connected to contacts 10A in the same manner as bus strip 40 is connected to contact 10. Since the gap between contact-engaging surfaces 48A on the bus strip is less than the transverse dimension between the flat, substantially parallel surfaces 94 of the contact 10A, adjacent legs 58A will be biased apart by their engagement with the flat surfaces 94 to thereby provide a resilient electrical and mechanical interconnection with the contact.

The first two voltage bus assemblies described. The loose contacts 10 or 10A are first assembled into the insulating housings 72 of the electrical connectors 70. The insulating housings 72 loaded with contacts 10 or 10A are then assembled on metal plate 80. Both the loading of the contacts within insulating housings 72, and the assembling of the electrical connectors 70 on the metal plate are accomplished by well-known, time-proven techniques and automatic equipment. After the electrical connectors are mounted on the metal plate, the bus strips 40 or 40A are inserted into the slots formed in the sidewalls 73 of the insulating casings 72 through the bifurcating slots of the contacts which are to be electrically interconnected, until contact-receiving slots 46 or 46A of the bus strip 40, 40A, respectively, are directly aligned with the bifurcating slots of the contacts. The bus strips 40 or 40A are then pushed downwardly toward the tail portion of the contacts to cause the legs 58 or 58A to electrically and mechanically engage with the contacts 10, 10A, respectively.

Referring now to FIGS. 7-10, the embodiment of the present case is shown. An elongated tail portion 16B (FIGS. 7 and 8) of the contact is bifurcated in the direction of elongation, by a slit 21B. The slit 21B is defined in part by four elongated chamfered surfaces 26B (FIG. 8). Slit 21B terminates in a base which is defined in part by chamfered surfaces 30B. The nose portion and body portion of the contact can be of any desired configuration; however, the slit tail configuration is ideally suited for making a bus connection between contacts having a nonbifurcated nose portion.

The bus strip 40B which is utilized in making the bus connection to the contact tail portions of the contacts is identical with the bus strip 40 shown in FIG. 2.

To make the bus connections, loose contacts are first assembled into an insulating housing 72B to form electrical connectors. The electrical connectors are then inserted into metal plate 80 in side by side relationship with the slit tail portion 16B of each contact extending below the bottom surface of

the plate. The slits in the tail portions of the contacts which are to be electrically interconnected lie in a common plane, and bus strip 40B is inserted into such slits. Chamfered surfaces 48B on the bus strip frictionally, electrically, and mechanically engage chamfered surfaces 26B on the tail portions.

To insure that the bus strip 40B does not separate from the contact tails 16B, and that the bus strip is properly positioned with respect to the contact tails, at least one retaining member 100 is provided. The retaining member has a bifurcated upper holding portion 102 defined by a pair of resilient legs 104. The outer periphery of the holding portion is provided with a slot 106 defining locking shoulders for engaging and holding the retaining member 100 has a bus strip receiving cavity 112 therein which is defined by resilient bus strip-retaining finger 108 having flanged lower sections 110 and an upper surface 114 having a positioning and stabilizing groove 116 formed therein. As bus strip 40 is inserted into slits 21B provided in the tail portions 16B, the bus strip urges the resilient bus strip retaining fingers 108 apart, until end surface 42B of the bus strip firmly seats against the base 116 of the positioning and stabilizing groove 116. In this position, the lower surface 44B of the bus strip 40B is positioned above the upper surfaces of flanged lower section 110 to permit bus strip retaining fingers 108 to return to their normally closed position. In this condition, the bus strip 40B is retained within bus strip receiving cavity 112, thereby preventing the bus strip from becoming separated from the tail portions 16B. Furthermore, when end surface 42B of the bus strip is in engagement with the base 116 of the positioning and stabilizing groove 116, the bus strip is properly positioned with respect to the tail portions 16B. In the assembled condition, inclined surfaces 50B provided on bus strip 40B do not engage the chamfered surfaces 30B of the tail portions. Such engagement could cause fingers 58B to be urged outwardly thereby impairing the electrical and mechanical connection between the chamfered surfaces 26B and chamfered surfaces 48B provided on the bus strip.

In FIG. 9, one retaining member 100 is shown positioned within an opening in metal plate 80 which is adjacent one longitudinal end of the bus strip 40B; however, it is within the scope of this invention to provide a pair of retaining members 100 for each bus strip 40B with each retaining members being positioned in an opening in metal plate 80 aligned with a longitudinal end of the bus strip.

I claim:

1. An electrical interconnection system comprising
  - a plurality of elongated electrical connectors mounted side by side on a supporting structure, each electrical connector having a longitudinally extending circuit board-receiving slot the longitudinal axis of each circuit board-receiving slot being parallel to the direction of elongation of its corresponding electrical connector;
  - at least one electrical contact disposed in each of two of said electrical connectors, each contact having a nose portion, an elongated tail portion, said nose and tail portions being interconnected by a body portion;
  - the tail portion of each contact being bifurcated in its direction of elongation by a slit which is defined, in part, by chamfered surfaces, said contacts being oriented such that said slits lie about a plane which is substantially perpendicular to said circuit board-receiving slots; and
  - a substantially flat elongated bus strip positioned within the slits in the tail portion of each contact, said bus strip having chamfered surfaces which frictionally engage the chamfered surfaces on said contacts.

2. The electrical interconnection system of claim 1, wherein each tail portion is provided with a pair of elongated chamfered surfaces on each side of the slit, said chamfered surfaces being elongated in the direction of elongation of said tail portion, said bus strip having substantially parallel elongated side surfaces and an end surface interconnecting said side surfaces, contact-receiving slots extending through said side surfaces from the end surface in a direction perpendicular to the

direction of elongation of said side surfaces, each contact receiving slot being defined, in part, by a pair of chamfered surfaces one each side of said contact-receiving slot, the chamfered surfaces on said bus strip frictionally engaging the respective chamfered surfaces on the tail portion of contact.

3. The electrical interconnection system of claim 2 wherein a retaining member is mounted within an opening in said supporting structure, said retaining member being positioned adjacent one longitudinal end of said bus strip and having means

for retaining said bus strip to prevent said bus strip from separating from said contacts.

4. The electrical interconnection system of claim 3 wherein a second retaining member is mounted within an opening in said supporting structure adjacent the end of said bus strip opposite said one longitudinal end, said second retaining member having means for retaining said opposite longitudinal end to further support said bus strip.
